(57) **CLAIM**

The ornamental design for a pump for an orthopedic device, as shown and described.

DESCRIPTION

FIG. 1 is a perspective view of a pump for an orthopedic device showing my new design.

FIG. 2 is an enlarged front elevational view according to the pump of FIG. 1 provided for better clarity of the pump.

FIG. 3 is an enlarged first side elevational view according to the pump of FIG. 1 provided for better clarity of the pump; and,

FIG. 4 is an enlarged opposite side elevational view according to the pump of FIG. 1 provided for better clarity of the pump. The broken lines illustrate environmental and supplementary structure and form no part of the claimed design.
